UNITED STATES PATENT OFFICE.

JOHN ARTHUR HUGHES, OF WACO, TEXAS.

TYPEWRITER DESK.

Application filed October 11, 1922. Serial No. 593,750.

To all whom it may concern:

Be it known that I, JOHN ARTHUR HUGHES, a citizen of the United States, residing at Waco, in the county of McLennan and State of Texas, have invented certain new and useful Improvements in Type-writer Desks, of which the following is a specification.

This invention has reference to type-writer desks of combination form including means for supporting an adding machine in connection with the typewriter whereby both machines may be used at the same time by separate operators, and provision is made for the storage of papers employed in connection with the typewriter and adding machine.

In accordance with the invention, there is provided a typewriter desk and adding machine support comprising a stand, a table that raises and lowers and two trays that operate in conjunction with the table so that when the table is raised, the two trays are lowered at the two sides of the table.

The purpose of the device is that it may be used as a bookkeeping desk with a typewriter on one end of the table and with an adding machine at the other end thereof and capable of carrying loose leaf ledger sheets or other records in the two trays, whereby two persons may work at one table and at the same time, one working at each end, and when the work is finished, then the device may be closed up, the table going down and the two trays coming up so as to be locked and then pushed into a vault, whereby to secure the safety of the records.

The table may be made to carry a typewriter and a hand operated adding machine or may be made to carry motor driven machines.

The invention will be best understood from a consideration of the following detailed description taken in connection with the accompanying drawings forming part of this specification, with the understanding that the invention is not confined to any strict conformity with the showing of the drawings, but may be changed and modified so long as such changes and modifications mark no material departure from the salient features of the invention as expressed in the appended claims.

In the drawings:—

Figure 1 is a plan view, with some parts

broken away, showing the combined desk and support in the extended position,

Fig. 2 is a side elevation, with some parts in section, showing the table and desk extended.

Fig. 3 is a side elevation showing the combined desk and table collapsed and elevated ready for storage in a vault,

Fig. 4 is a fragmentary elevation and section of one half of the collapsed structure,

Fig. 5 is an elevation and section taken at right angles to Fig. 4,

Fig. 6 is a fragmentary section and elevation of one end of the extended table,

Fig. 7 is a perspective view of a portion of the table in the extended position,

Fig. 8 is a fragmentary section of a portion of the table.

Referring to the drawings, there is shown a rectangular frame 1 including channel iron legs or uprights 2 joined at the top by cross pieces 3 which are connected by other cross pieces 4 near the bottom ends and the lower ends of the legs 2 terminate in castors 5, the parts being rigidly connected for storage in a vault or other receptacle.

The top of the table is occupied by a work supporting member 6 and the legs are joined by rods 7 and by bars 8 which bars terminate in angle members 9 dropping into the upper ends of the legs 2, the bars 9 carrying rollers 10 at the upper and lower ends thereof.

At each end of the bar 8 is connected by a pin 11 to one end of an angle lever 12 terminating at the end remote from the pin 11 in a handle 13 and also provided with a short arm 14 connected by a pin 15 to an intermediate portion of another lever 16 in turn connected at the end remote from the pin 7 with a cross rod 17 through the intermediary of a rocker arm 18 carried by the cross arm 17. There are two rocker arms 18 on opposite sides of the frame and these rocker arms are connected by respective links 19 at opposite ends so as to compel united movement of the levers 16 and the parts connected thereto.

Each lever 12 is connected by a pin or pivot 20 to the corresponding end of a casting or carrier 21 supported by the levers 12 exterior to the carrier 21 and by pairs of parallel links 22 within the carriers 21.

The carriers 21 support the angle links 23 exterior to the carriers 21 and the angle

links 23 are arranged in pairs to each carrier 21 at opposite ends thereof with one end of each link 23 supported by a lug 24, a cover member 25 for a respective carrier 21 and constituting a cover therefor which when open forms a shelf for books, papers, etc.

The inner side wall 27 of each container 21, there being two such containers on opposite sides of the machine, is connected to containers 21 and lids 25, by two links 22, one above the other, and one of these links 22 is connected by a broken elongated link 26 with the cover member 25 of the respective container 21, the arrangement being such that the cover member 25 and the side wall 27 are moved under the action of the links 22, 23 and 26, and when the cover member 25 is moved into and out of covering relation with the container 21, the member 27, is by the same operation reciprocated, the member 27 forming the inner wall of the containers 21.

When the parts are in the closed position ready for storage in a vault or other receptacle, said parts having the appearance shown in Fig. 3, the receptacles 21 being brought into close adjusted position over the frame of the structure with the receptacles 21 housed by the cover members 25 and 27, and the various levers located within the borders of the frame 1.

Now by grasping either of the handles 13 the levers 12 and parts connected therewith are moved away from the center of the structure to the position shown in Fig. 2.

The movement imparted to the levers 12 by the manipulation of the handles 13 causes the rocking of the levers 12 and 16 to the positions shown in Fig. 2, thus separating the receptacles 21 and establishing them on opposite sides of the frame 1.

When the two containers or trays 21 are separated, the action is to lower these trays alongside of the main frame 1 and raise the table 6, bearing typewriters, etc., to top of stand, the containers being for the reception of loose leaf ledger sheets or other records and the tables 6, carrying a typewriter or adding machine on each end whereby two people may operate at the same desk at the same time.

When it is desired to store the machine and its contents, the handles 13 are actuated, causing a lifting of the trays or containers 21 with their contents and the deposition of these trays without disturbing their relation to the structure on top of the table 1 with the covers 25 replaced in covering relation thereto above the table 1, all as shown in Fig. 3 of the drawing, whereupon the various parts may be locked in position enclosing the loose leaf papers or other documents and the whole structure being moved into a vault for safe keeping, whereby to insure the safety of the records.

Of course, it will be understood that the adding machine structure may be of a motor driven type or may be of the hand driven type with the machines, when in use, being suspended and lowered into convenient position for manipulation.

What is claimed is:—

1. In a typewriter desk, a movable support for a typewriter, filing sections arranged for movement directly over and to opposite sides of the desk, and means constructed and arranged for connection with the movable support and filing section for synchronous operation thereof whereby on movement of the filing sections to position over the desk the platform will be lowered and on reverse movement of the filing sections said platform will be raised.

2. In a typewriter desk, a movable support for a typewriter, filing sections arranged for movement directly over and to opposite sides of the desk, and means constructed and arranged for connection with the movable support and filing sections for synchronous operation thereof whereby on movement of the filing sections to position over the desk the platform will be lowered and on reverse movement of the filing sections said platform will be raised, movable top and side sections for each filing section and means connecting the same for movement of one when actuating the other.

3. In a typewriter desk, a movable support for a typewriter, filing sections arranged for movement directly over and to opposite sides of the desk, and means constructed and arranged for connection with the movable support and filing sections for synchronous operation thereof whereby on movement of the filing sections to position over the desk the platform will be lowered and on reverse movement of the filing sections said platform will be raised, and manually controlled means for actuating the first named means.

4. In a typewriter desk of the character described, a main supporting frame, a vertically shiftable platform within said frame, a pair of shiftable cases each adapted to be swung from a position over the frame to a position at opposite sides thereof and means connecting said platform with said cases whereby the latter will overbalance and raise the platform on initial movement of said cases from over the frame.

5. In a typewriter desk of the character described, a main supporting frame, a vertically shiftable platform within said frame, a pair of shiftable cases each adapted to be swung from a position over the frame to a position at opposite sides thereof and means connecting said platform with said cases whereby the latter will overbalance and raise the platform on initial movement of said cases from over the frame, a mov-

able top section for each case, a movable inner side section for each case, and means common to the respective cases and actuated by each top section when shifted to simultaneously shift the side section for the opening of the case.

6. In a typewriter desk of the character described, a main supporting frame having legs, said legs being hollow and having one side open through a portion of their length, a vertically shiftable platform within said frame, cross bars supporting said platform and extending within said legs for movement throughout the openings therein, laterally shiftable cases normally seated in and at the top of said frame, and means connecting said platform with said cases whereby the latter when swung laterally will overbalance and raise the platform.

20 7. In a typewriter desk of the character described, a main supporting frame having legs, said legs being hollow and having one side open through a portion of their length, a vertically shiftable platform with-
25 in said frame, cross bars supporting said platform and extending within said legs for movement throughout the openings therein, laterally shiftable cases normally seated in and at the top of said frame, and means
30 connecting said platform with said cases whereby the latter when swung laterally will overbalance and raise the platform, said means further acting as a support for said cases.

35 8. In a typewriter desk of the character described, a main supporting frame having legs, said legs being hollow and having one side open through a portion of their length, a vertically shiftable platform with-
40 in said frame, cross bars supporting said platform and terminating in depending angle members, rollers carried by said angle members one at the upper and one at the lower end thereof, for vertical movement
45 in said hollow legs, laterally shiftable cases positioned partially within the top of said frame, parallel revoluble cross bars connect-
ing the legs near the lower end thereof, vertical rock levers secured at their lower ends
50 to said cross bars, and linked with the cases at their upper ends, obtusely angled actu-
ating levers having one arm of greater length than the other, and laterally extending short arms on said long arms interme-
55 diate the bend and the end thereof, each of said short arms being pivotally connected to the rock lever adjacent thereto and each actuating lever being further pivotally connected, at the end of the long arm, to the platform and at the angle, to one end of one
60 of said cases.

9. In a typewriter desk of the character described, a main supporting frame having legs, said legs being hollow and having one side open through a portion of their length.

a vertically shiftable platform within said frame, cross bars supporting said platform and terminating in depending angle members, rollers carried by said angle members, one at the upper and one at the lower end thereof, for vertical movement in said hollow legs, laterally shiftable cases positioned partially within the top of said frame, parallel revoluble cross bars connecting the legs near the lower end thereof, vertical rock levers secured at their lower ends to said cross bars, and linked with the cases at their upper ends, obtusely angled actuating levers having one arm of greater length than the other, and laterally extending short arms on said long arms intermediate the bend and the end thereof, each of said short arms being pivotally connected to the rock lever adjacent thereto and each actuating lever being further pivotally connected, at the end of the long arm, to the platform and at the angle, to one end of one of said cases and means for compelling united movement between said rock levers.

10. In a typewriter desk of the character described, a main supporting frame having legs, said legs being hollow and having one side open through a portion of their length, a vertically shiftable platform within said frame, cross bars supporting said platform and terminating in depending angle members, rollers carried by said angle members, one at the upper and one at the lower end thereof, for vertical movement in said hollow legs, laterally shiftable cases positioned partially within the top of said frame, parallel revoluble cross bars connecting the legs near the lower end thereof, vertical rock levers secured at their lower ends to said cross bars, and linked with the cases at their upper ends, obtusely angled actuating levers having one arm of greater length than the other, and laterally extending short arms on said long arms intermediate the bend and the end thereof, each of said short arms being pivotally connected to the rock lever adjacent thereto and each actuating lever being further pivotally connected, at the end of the long arm, to the platform and at the angle, to one end of one of said cases, rocker arms secured midway their ends to said cross bars, and crossed link connection between the ends of said rocker arms for compelling united movement of the rock levers.

11. In a typewriter desk of the character described, a supporting frame, a vertically shiftable platform within said frame, laterally shiftable cases within and projecting above said frame, a shiftable top and inner side for each case, a pair of lugs upon the under side of each top at each end thereof, a pair of lugs upon each shiftable side at each end thereof, an angled and a broken link pivotally connected to each end of 130

each top by said lugs, the other end of each angled link being pivotally connected to the end adjacent thereto of the case, a pair of short links pivotally connecting said lugs on each shiftable side to the inner ends of said cases, said broken links having their other ends pivotally connected to one of said short links, said top and side of each case operating in unison to move the top laterally of said case in a horizontal plane and to move

the side outwardly and downwardly in a vertical plane, and means connecting the cases with said platform so that the lateral movement of the cases will raise the platform to the level of the frame and lower ¹⁵ the top edges of the cases to a plane approximately parallel with the platform.

In testimony whereof, I affix my signature hereto.

JOHN ARTHUR HUGHES.
